UNITED STATES PATENT OFFICE.

MAX RUBIN, OF PHILADELPHIA, PENNSYLVANIA.

BOTTLE-STOPPER.

SPECIFICATION forming part of Letters Patent No. 299,269, dated May 27, 1884.

Application filed March 17, 1884. (No model.)

To all whom it may concern:

Be it known that I, MAX RUBIN, of the city and county of Philadelphia, and State of Pennsylvania, have invented certain new and useful Improvements in Bottle-Stoppers, of which the following is a specification.

This invention has reference to an improved bottle-stopper of that class in which a cap closes the mouth of the bottle, said cap being pivoted to a neck-band that is guided in spiral grooves on the neck of the bottle, so as to raise or lower the cap; and the invention consists of a bottle the neck of which is provided with spiral grooves, and at intermediate points of the latter with vertical grooves, a neck-band guided thereon by projecting pins, and a cap having an annular flange and downwardly-extending arms pivoted to said pins, said cap being provided with an interior elastic disk.

20 In the accompanying drawings, Figure 1 represents a side elevation of my improved bottle stopper, showing it in closed position; Fig. 2, a vertical transverse section of the same. Figs. 3 and 4 are side views of the 25 same, showing the pivoted cap respectively in position raised above the bottle-mouth and in a position sidewise of the neck of the bottle; and Fig. 5 is a side view of the bottle-neck with the stopper detached.

30 Similar letters of reference indicate corresponding parts.

A in the drawings represents a bottle, which is provided with a cylindrical neck, B, having two spiral grooves, *b b*, at diametrically opposite sides of the same.

35 C is a ring-shaped neck-band, that is fitted to the cylindrical portion of the neck B; and D, a cap, which is provided with an annular flange, *e*, and at diametrically-opposite points 40 with downwardly-extending arms *D'*, that are pivoted to pins *d d* of the neck-band C. The pins *d d* project into the spiral grooves *b b*, and are guided in the same, so as to raise or lower the cap D. The cap D is made of suitable sheet metal, the arms *D'* and flange *e* being made integral therewith. When the bottle is to be hermetically closed by the cap, it is provided with an interior disk, *D²*, of rubber or other elastic material, which disk is 50 pressed closely on the mouth of the bottle

when the neck-band is moved along the grooves *b b* into its lowermost position on the bottle-neck. (Shown in Figs. 1 and 2.) The spiral grooves *b b* are preferably provided at their upper and lower ends with short horizontal portions, which serve as rests or seats for retaining the neck-band in raised or lowered position. When the neck-band C is turned in opposite direction until the pivot-pins arrive at the upper horizontal portions of the spiral 60 grooves *b b*, the cap D is raised to such an extent above the bottle-mouth that it can be thrown on the pivot-pins *d d* into open position sidewise of the bottle-neck, as shown in Fig. 4. In this position of the cap the bottle 65 is readily filled or emptied.

To place the bottle-stopper in position on the neck of the bottle, the spiral grooves *b b* are provided, at a point intermediately between the horizontal ends or seats, and at 70 opposite points of the bottle-neck, with vertical grooves *b' b'*, that extend to the upper edge of the neck B. When the cap D is to be placed in position on the bottle-neck, the pivot-pins *d d* are inserted in the vertical 75 grooves *b' b'* and moved downwardly along the same until they arrive in the spiral grooves *b b*. By then turning the cap along the grooves *b b* until they arrive at the lower ends of the spiral grooves *b b*, the bottle-cap is tightly 80 pressed on the mouth of the bottle, so as to close the same in a reliable manner.

Having thus described my invention, I claim as new and desire to secure by Letters Patent—

In a bottle-stopper, the combination of a 85 bottle-neck, B, having spiral grooves *b b* and vertical grooves *b' b'* at intermediate points of the spiral grooves, a neck-band, C, a bottle-cap, D, having arms *D'* pivoted to said neck-band, and an interior elastic packing, *D²*, the 90 pivot-pins of the cap projecting into and being guided in said grooves, substantially as set forth.

In testimony that I claim the foregoing as my invention I have signed my name in presence of two subscribing witnesses.

MAX RUBIN.
